[57] CLAIM

The ornamental design for a folding wall-mounted seat, as shown.

DESCRIPTION

FIG. 1 is a front perspective view of a folding wall-mounted seat in accordance with our design, in which the seat is shown in a closed position;

FIG. 2 is a front elevational view of the seat as shown in FIG. 1;

FIG. 3 is a top plan view of the seat as shown in FIG. 1;

FIG. 4 is a right side elevational view of the seat as shown in FIG. 1;

FIG. 5 is a bottom view of the seat as shown in FIG. 1;

FIG. 6 is a front isometric view of the folding wall-mounted seat or the like shown in an open position;

FIG. 7 is a front elevational view of the seat as shown in FIG. 6;

FIG. 8 is a top plan view of the seat as shown in FIG. 6;

FIG. 9 is a right side elevational view of the seat as shown in FIG. 6; and,

FIG. 10 is a bottom view of the seat as shown in FIG. 6.
